UNITED STATES PATENT OFFICE.

WILLIAM CLARK, OF BULGER, AND THOMAS BEADLING, OF CARNEGIE, PENNSYLVANIA.

TROLLEY-WIRE SPLICE.

1,125,816.

Specification of Letters Patent.

Patented Jan. 19, 1915.

Application filed February 18, 1914. Serial No. 819,568.

To all whom it may concern:

Be it known that we, (1) WILLIAM CLARK and (2) THOMAS BEADLING, citizens of the United States of America, residing at (1) 5 Bulger and (2) Carnegie, in the counties of (1) Washington and (2) Allegheny and State of Pennsylvania, have invented certain new and useful Improvements in Trolley-Wire Splices, of which the following is a specification, reference being had 10 therein to the accompanying drawing.

This invention relates to trolley wire splice, and has for its object to provide a device of such class, in a manner as herein- 15 after set forth, with means to permit of adjusting the length of the splice member or for decreasing the length of said member to maintain the trolley wire taut.

Further objects of the invention are to 20 provide a trolley wire splice, which is simple in its construction and arrangement, strong, durable, efficient and convenient in its use, readily set up and comparatively inexpensive to manufacture.

With the foregoing and other objects in view, the invention consists of the novel construction, combination and arrangement 25 of parts as hereinafter more specifically described and illustrated in the accompanying drawings, wherein is shown an embodiment of the invention, but it is to be understood that changes, variations and modifications 30 can be resorted to which come within the scope of the claim hereunto appended.

In the drawings wherein like reference 35 characters denote corresponding parts throughout the several views: Figure 1 is a side elevation of a trolley wire splice in accordance with this invention, Fig. 2 is 40 an elevation partly in longitudinal section, and Fig. 3 is a cross sectional view.

A trolley wire splice in accordance with this invention consists of a member formed of two sections, one of which is indicated 45 at 4 and the other at 5. Each of the sections is formed with an annular groove 6 and an inclined opening 7, the latter ex- 50 tending from the bottom to the top of its respective member and communicates at its lower end with the inner terminus of the groove 6. The opposing ends of the sections of the trolley wire are mounted in the groove 6 and extend up through the

opening 7 and are clamped to the members 4 and 5 through the medium of clamping 55 screws 8, which have threaded engagement with the said members 4 and 5 and are adapted to extend in the opening 7 to engage the sections of the trolley wire where- 60 by the sections of the wire are fixedly se- cured to the members 4 and 5.

The member 4 includes lateral extensions 9 and 9^a a longitudinally extending pocket 10 and a longitudinal groove 11 arranged below the pocket 10. The section 5 is 65 formed with an inwardly extending offset 12 having formed integral therewith a pair of tongues 13 and 14, and a pocket 14^a, the tongue 14 being arranged below and of less thickness than the former. The pocket 10 70 is rectangular in contour and the tongue 13 in cross section is of the same contour as the pocket 10. The tongue 13 snugly fits into the pocket 10 and is provided throughout with transverse openings 15, any one 75 of which is adapted to register with a transverse opening 16, which is intersected by the pocket 10. The tongue 13 is detach- 80 ably connected to the section 4 through the medium of a bolt 17, which extends through the opening 16 and that opening 15 which alines therewith. The bolt 17 is provided with a head 8 and interposed between said head and projection 10 is a shoulder 20. The bolt 17 projects through the extension 85 9 and has the projecting end thereof threaded. Engaging with the threaded end of the bolt 17 is a nut 19 and interposed be- 90 tween the nut and the extension 19 is a shoulder 20. The tongue 11 extends into the groove 14^a and has its inner face inclining in a direction toward the free terminus of said tongue. The groove 14^a extends at an opposite inclination with respect to the inner face of the tongue 14. 95

What we claim is:—

A trolley wire splice comprising a mem- 100 ber formed of two inter-locking sections, one of said sections provided with upper and lower lateral extensions forming a lon- 105 gitudinal pocket, the other of said sections provided with an upper and lower tongues forming a longitudinal groove adapted for the reception of the lower of said lateral ex- 110 tensions and one of said longitudinal grooves being adapted for the reception of

the upper of said tongues, said last named tongue provided with transverse openings, that section provided with a pocket having an opening adapted to aline with one of the tongue openings, and a bolt extended through said alining openings for detachably connecting the sections together.

In testimony whereof we affix our signatures in the presence of two witnesses.

WILLIAM CLARK.
THOMAS BEADLING.
